UNITED STATES PATENT OFFICE.

WILL F. ALLEN, OF NASHVILLE, TENNESSEE.

DESIGN FOR A STOVE.

Application filed April 24, 1924. Serial No. 9,386. Term of patent 7 years.

To all whom it may concern:

Be it known that I, WILL F. ALLEN, a citizen of the United States, and a resident of Nashville, in the county of Davidson and State of Tennessee, United States of America, have invented a new, original, and ornamental Design for a Stove, of which the following is a specification, reference being had to the accompanying drawings, forming part thereof.

Figure 1 is a perspective view of a stove embodying the new design.

Fig. 2 is a rear view thereof.

I claim:

The ornamental design for a stove, as shown.

WILL F. ALLEN.
